APPARATUS FOR SYNCHRONIZED PROJECTION OF PICTURES AND MUSIC ON FILM

Jack S. Wendover, Los Angeles, Calif., and Charles F. Webber, Minneapolis, Minn.

Application June 5, 1947, Serial No. 752,672

6 Claims. (Cl. 88—24)

1

This invention relates to apparatus for synchronized projection of music on film, and more particularly to such apparatus, as will keep each member of an orchestra constantly supplied with the proper music, merely by setting of a dial on leader's stand.

To carry sheet music to give a selection of several hundred numbers, amounts to a considerable burden for each instrument. When the orchestra is large, it becomes enormous. Also, unless each member keeps it well indexed and in proper order, it results in confusion. In any event, much time is spent in finding and changing music, and it is always an unpleasant disturbance. Although the lighting might be considered good, there may be glare in some cases, and shading by other members in other cases, so that the music is difficult to read, and with lights dimmed, it may be very difficult.

One important object of our invention is to provide all the music required for a great number of selections for a large orchestra, in such small bulk and weight, that it can be carried and kept in possession of one person.

Another object is to relieve members of an orchestra of all chores, except playing their instruments, each member having constantly before him the music he is to play, and obviating all confusion and mistakes as to the proper sheets of music.

Another object is to render music easily readable under all circumstances, by proper light application from a source within a cabinet, projecting music on a screen in top of cabinet.

Another object is to provide automatically controlled projection of music, for each member of an orchestra, at reasonable expense.

Other objects will be apparent from the description and appended claims.

For a full disclosure of our invention, reference is made to the description following and to the drawings, in which—

Fig. 1 is an elevation view, with parts in section to show apparatus. A leader's cabinet is shown at A, one of several musicians' cabinets at B, and a flat lying cabinet for piano at C.

Fig. 2 is a front elevation view of a musician's cabinet, showing interchangeable display of insignia of orchestra.

Fig. 3 is a larger scale plan view, showing details of film on driving pulley, with position indicator, film band splice with marking and idler pulley adjustment.

Fig. 4 is wiring diagram for motors, projector and light for one cabinet.

2

In the selected embodiment of our invention, which is hereby disclosed, we provide cabinets 10 for each of the musicians, and a cabinet 11 for the leader. These cabinets, provided in lieu of music stands, are preferably of wood, but might be made of other materials. Into each of the cabinets 10, we install a projector 12, with film 13 on several special film handling pulleys, to be described later, two self synchronous motors 14 and 15 in parallel, for turning film on pulleys, to be further described later, and a projection screen 16, consisting commonly of a frosted glass plate. Into the leader's stand, we make a like installation, and in addition, install a motor 17, which will be later described, a gear train 18 and a dial 19. Except for a more convenient location for the dial, it could be coaxially connected to the motor 17, as the gear train 18 has a ratio of unity and serves no other purpose, except providing a more convenient location for the dial. The motors 14 and 15 act as receivers, and the motor 17 acts as a transmitter. These motors are of the type, that are self-synchronous, and receiving units follow all movements of the transmitter, and indicate simultaneously at several remote stations. Actually the transmitter operates as a generator, and receivers operate as motors. Principle of operation is the balance of induced voltages, which results in rotor of receiver taking exact corresponding position, to that of rotor of transmitter. The leader, by use of the transmitter in his cabinet, controls the many receivers in cabinets of orchestra members, so that the same selection, with the proper music for each instrument, is projected from the film and thrown on the screen, provided by the frosted glass plate in inclined top of each of the stands. All motors are connected in parallel, and the apparatus can be plugged into the common alternating current single phase lighting circuit. If the current is three phase, wiring to make use of only one of the phases, is of course necessary. The two motors 14 and 15 acting as receivers, are again connected in parallel with each other, and the reason two are used, is to minimize overshooting and attain the required accuracy. The motors are of the high accuracy type, but a variation of one degree is possible, with a single motor. By joining in parallel a second receiving motor, this variation is reduced to a small fraction, which, with latitude available in screen, projector opening and focus, comes well within the accuracy required. The second motor, to which the increased accuracy is applied, is connected 50 coaxially with one of said pulleys, which acts

as a driving pulley, to be described later, to change frames of film 13 projected on screen 16.

In both cabinets 10 and 11, the projector and film handling and driving apparatus is housed in a drawer 20, which may be pulled out to easily change the film band, and make any adjustments necessary. This drawer may pull out in the rear or on the side, and in the case of the cabinet for a piano, may pull out at the end. The leader's cabinet is also provided with a light translucent panel 21, over which, an index of music numbers is easily inserted. This index shows selections numbered in accordance with the numbers on the dial, so that by turning dial indicator to the number opposite the selection shown on the index, the music for that selection will be projected on the different cabinet screens. A light 22 is provided on all musicians' cabinets for emergency, and on leader's cabinet likewise and to facilitate reading of index and turning of dial. Rarely, will the light be used by musicians in connection with projected music, but it is available for playing from sheet music, in an emergency. A light translucent panel 23 is provided in the front of each of musicians' cabinets 10, into which, can be inserted a display of the orchestra's insignia, and which is lighted up from within by the projector 12. Power and light circuits 24 and 25 respectively, with switches 26 and 27 respectively, are provided leading to, joining and governing the different devices.

The set-up disclosed, employs standard film of 8 mm. width and with 4 mm. by 5 mm. frames. It uses two film frames for each double sheet of music, which is ordinarily sufficient for each selection. Since sheet music is mostly 7" x 10½" and some 9½" x 12", when folded, resulting in 14" wide by 10½" high and 19" wide by 12" high respectively, the proportion is proper to photograph a double sheet on two film frames. The screen proportions are likewise proper for this film size, so with a standard projector altered as to opening and lens, so as to properly project two film frames at a time of 8 mm. film, the apparatus works out well. A system can of course be devised to photograph 8 mm. film, so a double sheet of music will appear on a single film frame 4 mm. x 5 mm. in cross direction on the film, and then passed through projector to be accommodated on the screen 16, by re-positioning projector or by guiding film to pass through projector in a direction at right angles to that shown. With 8 mm. film length for each selection, and assuming a dial with 360 divisions, the film band is fitted into cabinets with guiding pulleys 28, a driving pulley 29 and adjustable idler pulleys 30, as shown on the drawing. The driving pulley 29 has sprocket teeth to engage perforations in film, and working in conjunction with guiding pulleys 28 and adjustable idler pulleys 30, govern exact movement of film in either direction. A splice 31 accurately secures ends of film, so that an endless band is formed and carries a mark to set to for registry. Other film sizes and dial divisions may of course be devised and used. An indicator 32 is provided, to which all film bands are set to register. With identical mechanical set-up in each cabinet, and with transmitter and receivers in such close accuracy with each other, a selection may be had of any number, either forward or backward or anywhere on the film band. The receivers run forward or backward, whichever way transmitter is turned, and may be step by step either way or selective by either the shorter or longer way, whichever is selected.

A customary adjusting screw 33, provides for movement back and forth of the lens holder 34 of the projector, to bring same into proper focus. To provide for close adjustment of film band, 5 to take care of any variations and attain closely identical mechanical setups, adjusting plates 35 are applied to each of the idler pulleys 30. The pulleys are constantly spring mounted to adjusting plates, by brackets 36 slidable bars 37 and springs 38, to maintain the necessary amount of tension, after proper setting of adjusting plates. The film bands, when not mounted for projection, are loosely wound and stored on reels. A modification of the use of a film band, consists 10 of a belt or endless chain rack, for inserting separate frames of film of music in the order desired, eliminating need to cut and splice film, to make changes in numbers of a selection. Where cabinets of such small size are desired, 15 so as to require installation of apparatus in an abnormal position, and also create too much heat in too close proximity to the film, it is possible to make use of a right angle prism of glass or a mirror at 45°, to solve the problem, by 20 turning light beams in a right angle.

If the orchestra or band is large, so that there are too many receivers to be handled by a single transmitter, then a second or third transmitter is installed in parallel with the first transmitter, 25 and in turn, the allowable number of receivers hooked up with each transmitter. Usually, a transmitter will control eight sets of two receivers each. Capacitors may be also used to reload the line, so that additional receivers may be handled.

We do not claim herein specifically, structure 30 of any of the elements, but in the particular new assembly of elements, which coact in a new way to bring about new and beneficial results, long desired but not heretofore attained. It is the 35 product of the simultaneous or successive action of all the elementary parts, viewed as one entire whole, that is involved.

From the foregoing, it is apparent how the apparatus works. The setting of dial on the leader's stand, accordingly results in a similar setting 40 at all the other stands, and a change by the leader from one panel or sheet to the next, step by step or to another number elsewhere on the film, likewise simultaneously takes place at all 45 the other stands. Each stand has the music film with the particular arrangement, prepared 50 for its particular instrument, and arranged in corresponding order on the film. Each member has constantly before him, the music he is to play, 55 without any effort or responsibility on his part, and with no chance of confusion or mistake. The music is turned for him. It increases control 60 of conductor over a large band or orchestra. In concerts and opera, music can be improved or accomplished with less effort, as the director and all members have the additional freedom to concentrate, as to time of play of different parts and putting more emphasis into the music. At the 65 same time, the burden of carrying the bulk represented by a large number of selections for a large orchestra, is eliminated. Also, there is proper light application at all times, from a source within a cabinet, projecting music on a screen in top of cabinet. What would otherwise 70 cause shadows, is of no effect, and lights of the hall may be dimmed and the music can be read even better. Music publishers can instead of printing, film the music, thereby opening up a new field for them, and thus there would be no 75 controversy in regard to copyright. The appa-

status, however, is not limited to use in the field of music. It will serve as well for projecting radio script on screens for participants, facilitating greatly in dramatic productions, in giving additional freedom in playing parts and giving opportunity to do other things to better the production, like prompting and signalling others, adding effects, timing and more gusto. It eliminates use and turning of script paper, which creates much disturbing noise in broadcasting. With more use of television in the offing, its application will be further similarly extended.

What we claim is:

1. In a system of the class described, in combination, a plurality of wood cabinets, a drawer in bottom portion of each adapted to open out in a convenient direction from said cabinet to hold projector apparatus, a frosted glass screen in each of said cabinets inclined at a convenient angle for vision, an exterior downward directed light over top of each of said cabinets, one of said cabinets being of greater dimension than other cabinets and having in its top a partly transparent panel illuminated from within for an index, and each of said other cabinets having a partly transparent panel in an easily seen location for an interchangeable insignia display illuminated from within, a projector apparatus in drawer of each cabinet, a film with music recorded thereon of proper proportions for projection on said screen, a driving pulley and a plurality of guiding pulleys and idler adjusting pulleys for said film, two self-synchronous motor receivers in every cabinet having circuit connections in parallel with each other and one having axial connection to said driving pulley, a self-synchronous motor transmitter in said greater dimension cabinet connected in parallel to said receivers and adapted to direct movement of said receivers, a dial on said cabinet having a gear train connection to said transmitter to select music to be projected, and circuits for all power and light including terminal boxes and switches.

2. In a system of the class described, in combination, a plurality of wood cabinets, one of which is larger than the other cabinets, a projector apparatus for every cabinet, two self-synchronous motor receivers for every cabinet, a self-synchronous motor transmitter for said larger cabinet, a controlling dial for transmitter, and light and power circuits; each of said cabinets having a drawer in bottom portion thereof to hold said projector apparatus, a frosted glass screen in top conveniently inclined for good vision, an exterior downward directed light over said top, said larger cabinet also having in addition, a similarly inclined glass display panel for an index, all other cabinets having also a vertical glass panel for interchangeable insignia display, all display panels being illuminated from within; said projector apparatus consisting of a housing, a light source, a lens adjustable relative to said light source, a film band with music recorded thereon, a driving pulley and a plurality of pulleys for guiding and adjusting said film; said self-synchronous motor receivers having circuit connections in parallel with each other and one of said receivers having mechanical connection to said driving pulley; said self-synchronous motor transmitter having circuit connections in parallel with said receivers and adapted to direct movement of said receivers in either direction to drive said pulley; said controlling dial for transmitter on said larger cabinet having a gear train engaging with said transmitter and graduations

on said dial to correspond with numbers on said index in cabinet, which correspond to music numbers on said film; said light and power circuits including switches and terminal boxes and leading from common lighting circuit, having modifications consisting of secondary circuits for power.

3. In a system of the class described, in combination, a plurality of cabinets, one of which is of greater dimension than other cabinets, a drawer in each of said cabinets, a projector in said drawer, a film with music recorded thereon for said projector, an inclined screen in top of said cabinets for projection of said film, an electric lamp over each cabinet, a vertical light translucent panel in each of smaller cabinets adapted to exhibit interchangeable insignia, an inclined light translucent index panel in top of said greater dimension cabinet, a driving pulley and a plurality of guiding pulleys and spring mounted adjusting idler pulleys in each cabinet for said film, means for driving each of said driving pulleys consisting of a pair of self-synchronous electrical receiving devices in parallel connection, as many as eight pairs of which are controlled simultaneously by a self-synchronous electrical transmitting device in parallel connection with said first mentioned devices, and arranged so that induced voltages are balanced and said first mentioned devices take corresponding position of that to which second mentioned device may be turned, said first mentioned pair of devices co-acting to reduce any overshooting to a very slight amount and when so required, a second and a third of said second mentioned devices may be connected in parallel to the first to accommodate a greater number of said first mentioned devices, a dial on said greater dimension cabinet with gear connections to said second mentioned device with markings corresponding to said index and to music recorded on film, and circuits including switches and terminals for said lights and modified to be adapted to said means but originating from an alternating current single phase lighting circuit.

4. In a system of the class described, in combination, a plurality of cabinets, one of which is a larger cabinet, the others being smaller cabinets and arranged in vertical or horizontal position to suit, a drawer in each of said cabinets, a projector in said drawer, a film with music recorded thereon for said projector, an inclined screen in top of said cabinets for projection of said film, an electric lamp in position to light exterior of top of said cabinets, said projector, film and screen having arrangement whereby two film frames at a time are projected and accommodated by screen, each two frames as a general rule comprising one selection reproduced on film from an opened sheet of standard sheet music, a vertical light translucent panel in each of smaller cabinets arranged for insertion of insignia display, an inclined light translucent panel with index in top of said larger cabinet, a driving pulley and a plurality of guiding pulleys and adjusting idler pulleys for said film, a pair of self-synchronous motor receivers for every cabinet, and in addition for said larger cabinet, a self-synchronous motor transmitter, each pair of receivers having circuit connections in parallel with each other to minimize overshooting, one of said receivers having direct connection to said driving pulley, said transmitter having circuit connections in parallel with said receivers and adapted to direct rotation of said receivers in either direction to drive

said pulley, a dial on said larger cabinet gear train connected to said transmitter, markings on said dial corresponding to numbers on said index and film to bring position of film selection into registry for projection by turning dial to number selected from index, and circuits for illumination, projection and power including switches and terminals.

5. In a system of the class described, in combination, a plurality of wood cabinets, a drawer in each cabinet, a projector apparatus in each drawer, a screen in each cabinet positioned to accommodate said projector apparatus and positioned for good vision from rear of said cabinet, an exterior downward directed light over top of each cabinet, one of said cabinets being of greater dimensions than other cabinets and having a translucent panel for an index along side of said screen, said panel being susceptible to projector apparatus light from within cabinet and said exterior downward directed light from without, each of said other cabinets having a translucent panel for an interchangeable insignia display illuminated from within, a film with music, radio script, dramatic instructions and the like recorded thereon of proper proportions for projection on said screen, said film being so arranged in direction that it passes through projector according to whether selection is photographed lengthwise or cross-wise of film that it is accommodated by said screen, a driving pulley and a plurality of guiding pulleys and idler adjusting pulleys for said film, two self-synchronous motor receivers in every cabinet having electric circuit connections in parallel with each other and mechanical connection of one to said driving pulley, a self-synchronous motor transmitter in said greater dimension cabinet connected in parallel to said receivers and adapted to direct movement of said receivers, means in connection with transmitter in said greater dimension cabinet by which movement of receivers as directed by said transmitter moves film to desired selection by using of reference number shown on index, and electrical circuits for illumination, projection and power including switches and terminals.

6. In a system of the class described, in combination, a plurality of wood cabinets, one of which is larger than the other cabinets, a frosted glass screen over opening in inclined top of each of said cabinets, a downward directed light over top of each cabinet, a drawer in bottom portion of each cabinet, a projector mounted in each of said drawers, a translucent panel in inclined top of said larger cabinet to accommodate an inter-

changeable index, a translucent vertical panel inside of each of the other cabinets to accommodate interchangeable orchestra insignia displays, a movable belt like member carrying a series of musical selections on film units arranged for projection on said screen, a driving pulley and a plurality of guiding pulleys and idler adjusting pulleys for said belt like member, said projector being positioned to light up translucent panels for index and insignia as well as project said film units, and having means to turn light source in a right angle by arranging angle of reflection equal to angle of incidence on a reflecting medium, so that a smaller cabinet may be used and also to lessen effect of heat on projected film units, two self-synchronous motor receivers in every cabinet, a self-synchronous motor transmitter in said larger cabinet, one of said motor receivers having direct connection to said driving pulley, a system of circuits whereby induced voltages are balanced so that said two motor receivers always take a position corresponding to position of said transmitter and by using two motor receivers, any slight variation of position is reduced to nearly nil and when the number of receivers exceeds a determined number, a second and a third transmitter may be joined to said transmitter and these in turn joined to an equal number of receivers to accommodate a greater total number of cabinets, a manually operated selector in definite connection to transmitter in said larger cabinet having a corresponding series of numbers to numbers of musical selections and to numbers of index to cause said receivers to turn film to any desired selection.
